DESIGN FOR A HANDBAG

Marie M. Deutz, New York, N. Y.

Application September 24, 1945, Serial No. 122,284

Term of patent 3½ years

(Cl. D87—3)

To all whom it may concern:

Be it known that I, Marie M. Deutz, a citizen of the United States of America, residing in New York city, county of New York and State of New York, have invented a new, original, and ornamental Design for a Handbag, of which the following is a specification, reference being had to the accompanying drawing, forming part thereof, wherein:

I claim:

The ornamental design for a handbag, substantially as shown.

MARIE M. DEUTZ.
